UNITED STATES PATENT OFFICE.

IRA D. WORCESTER, OF PITTSBURG, PENNSYLVANIA.

TOY.

SPECIFICATION forming part of Letters Patent No. 733,108, dated July 7, 1903.

Application filed July 19, 1902. Serial No. 116,247. (No model.)

To all whom it may concern:

Be it known that I, IRA D. WORCESTER, a citizen of the United States, and a resident of Pittsburgh, in the county of Allegheny and State of Pennsylvania, have invented a new and Improved Toy, of which the following is a full, clear, and exact description.

This invention relates to improvements in that class of toys called "tick-tacks," the object being to provide a toy of this character that may be readily attached to a smooth surface, such as glass, and held by atmospheric pressure and operating to cause a ticking noise to attract attention to goods displayed in a window, or to afford amusement.

I will describe a toy embodying my invention and then point out the novel features in the appended claims.

Reference is to be had to the accompanying drawings, forming a part of this specification, in which similar characters of reference indicate corresponding parts in all the figures.

Figure 1 is a perspective view showing a toy embodying my invention as applied to a window-glass. Fig. 2 is a sectional view of the toy. Fig. 3 is a section showing a modification.

The toy comprises a body portion 1, consisting of a yielding material—such, for instance, as a rubber. The body is concavo-convex, and arranged to project inward from the inner side of the toy is a tapping device 2, which in Fig. 2 is shown as a sphere of metal or other hard substance. It is seated in a socket 3, formed in the body. On the outer side at the center is a knob 4, formed integral with the body and designed for the attachment of a string 5.

In Fig. 3 the tapping device consists of a

hemispherical portion 6—such, for instance, as the head of a tack—and having a point 7 may be forced through the body and into the knob 4. It is to be understood that the opening in which the point 7 is inserted is equivalent to the socket shown in Fig 2.

In operation the device is attached to a window-glass or the like by pressing the same thereon to exclude a portion of the air, thereby forming a partial vacuum, so that the device will be held in place by the outer atmospheric pressure. Then by alternately drawing and releasing the string the tapper will be caused to make a sound on the glass. If desired, the cord may be provided at suitable intervals with knots 11, and then by drawing the thumb and finger over these knots the body portion will be rapidly vibrated.

Having thus described my invention, I claim as new and desire to secure by Letters Patent—

1. A toy comprising a body of flexible material having a socket member and a knob formed on the outer side integral with the body, and a tapper supported in said socket, substantially as specified.

2. A toy comprising a concavo-convex body of flexible material having a socket member on its inner side, a tapper of hard material seated in said socket, and a device on the outer side of the body to which a cord may be attached, substantially as specified.

In testimony whereof I have signed my name to this specification in the presence of two subscribing witnesses.

IRA D. WORCESTER.
